[57] CLAIM

The ornamental design for a liquid soap dispensing container, as shown and described.

DESCRIPTION

FIG. 1 is a top, front, and right side perspective view of a liquid soap dispensing container showing my new design;

FIG. 2 is a top plan view thereof;

FIG. 3 is a bottom plan view thereof;

FIG. 4 is a side elevational view thereof;

FIG. 5 is an opposite side elevational view thereof; and

FIG. 6 is a front elevational view thereof, the rear being identical in appearance.

FIG.1

FIG.2

FIG. 3

FIG. 5

FIG. 4

FIG. 6
